REFRIGERATOR DOOR

Willard W. Carroll, Kalamazoo, Mich.

Application November 26, 1937, Serial No. 176,617

9 Claims.

(Cl. 62—89)

This invention relates to improvements in refrigerator doors.

The main objects of my invention are:

5 First, to provide a novel and improved structure combining a refrigerator door and a compartment or pan pivotally mounted thereon and adapted to prevent dehydration of fruits or vegetables stored therein.

10 Second, to provide a refrigerator door having hydrating means associated therewith whereby to conserve the space in a refrigerator normally occupied by conventional hydrating boxes and the like.

15 Third, to provide an insulated door having the insulated portion thereof partially removed to provide room for a hydrator pan, said hydrator pan providing a dead air space to perform the insulating function of the insulating material removed from the door.

20 Fourth, to provide a refrigerator door having hydrating means associated therewith which is readily accessible and easily manipulated to expose the contents thereof.

25 Fifth, to provide a hydrator for use in combination with a refrigerator door, the said hydrator being open sided in nature and being closed by the door itself or a part of the refrigerator when in operative position to completely shield the contents thereof from the air circulation within the refrigerator.

30 Sixth, to provide a hydrating pan or element adapted for use in combination with a door and being self-closing in operative closed position, whereby to shield the contents thereof from air circulation in the refrigerator.

35 Further objects relating to details and economies of my invention will definitely appear from the description to follow. The invention is defined in the claims.

40 A structure embodying the features of my invention is illustrated in the accompanying drawing, wherein:

45 Fig. 1 is a view in vertical section through a refrigerator door embodying the hydrating pan or element of my invention.

Fig. 2 is a fragmentary inside perspective view with the hydrator in closed position.

50 Fig. 3 is an enlarged fragmentary detail view in horizontal section illustrating the mounting of the hydrating element on a refrigerator door.

Fig. 4 is a fragmentary view in vertical section similar to Fig. 1 with the hydrating pan or element removed, illustrating a preferred form of pivotal mounting therefor.

55 Figs. 5, 6, and 7 are fragmentary views in

vertical section illustrating modified embodiments of my invention.

In present day refrigerators an objection is usually present in the fact that due to the circulation of refrigerated air inside the box of the refrigerator vegetables, fruits and the like which are exposed to the currents of air are rapidly dehydrated and accordingly deteriorated. This effect is common and well known to any housewife. To combat the same, the expedient 10 has been adopted of furnishing each refrigerator with a separate covered box adapted to contain articles which are deteriorated by the dehydration effect mentioned, the said boxes being placed on the shelves and removed as desired. 15

These boxes are quite unsatisfactory. A certain amount of dehydration occurs even when they are used, due to air circulation therein, and in addition they are open to the further important objection that they occupy a large amount 20 of space inside the refrigerator whether they are full or empty. Moreover, they are bulky and difficult to handle inasmuch as they must be entirely withdrawn from the refrigerator, placed 25 on a supporting surface while the top is removed, then replaced, the operation requiring the use of both hands and consuming a considerable length of time.

It is the purpose of the present invention to 30 entirely eliminate the objections characterizing such individual boxes or receptacles and to secure all the benefits thereof. In general, my invention consists of a pan or container hinged to a refrigerator door, the latter having a certain 35 amount of the insulating material normally found therein removed to provide a recess to accommodate the pan or hydrator element. This in no way detracts from the insulating properties of the door inasmuch as a dead air space 40 is furnished by the receptacle which is fully effective for the purpose of quite uniformly insulating the door; at the same time the resultant structure projects very little beyond the normal inner surface of the door and, moreover, is easily and quickly manipulated to remove articles 45 therefrom.

Referring to the drawing, reference numeral 1 indicates a refrigerator door of usual construction having insulating material 2 therein and including metal inner and outer shells 3, 4. 50

In the case of the present invention, the inner shell 3 is formed to provide a recess 5 of substantial size, the insulating material normally in that space being removed and a suitable filler 55

member 6, preferably non-metallic, being employed to stiffen and strengthen the door.

As illustrated, the said recess 5 is formed adjacent the lower edge of the door, in fact, immediately above the beveled edge or pan 7 thereof. It will be apparent that this particular disposition is not essential in my invention, but is a convenient one inasmuch as the ordinary arrangement of shelves in the refrigerator provides 10 a larger vertical opening to receive the pan adjacent the lower portion.

At opposite sides of the recess 5 I provide hinge or pivot plates 8, each having an angled slot 9 thereon, said slot being provided with an enlarged inner end 10 to receive oppositely disposed pintles 11 on the pan or hydrator element 12. The removable pivot means enables the pan to be withdrawn from the door for cleaning when desired. This pan is shaped in general to correspond to the shape of recess 5 and is mounted therein by the pintles 11 as described, for free pivotal movement outwardly as indicated in dotted lines in Fig. 1. The pan has an open side which is completely closed by the door in operative position of the pan. If desired, the lip 13 of the pan may be bent upon itself to provide an enlarged lug engageable behind a suitable spring detent 14 secured to the door, said lug and detent frictionally retaining the pan in closed position. However, if desired, such locking means may be omitted and the mere frictional engagement of the pan with the recess be relied on to retain the former in closed position. A handle 15 is provided to facilitate manipulation thereof.

From an inspection of Fig. 1, it will be seen that the fitting of the pan in the recess is quite exact in order to prevent any unwanted circulation of air within the hydrating element. To this end, the said element is provided with a substantial bottom 16 adapted to engage lower ledge 17 throughout a sufficient area to effect a good seal at this point. Likewise, the spring detent 14 urges the upper lip 13 against the wall of the recess or other convenient part of the refrigerator to seal the element at this point. The result of these provisions is an effectively insulated volume largely within the normal outline of the door and only protruding slightly therefrom, the said volume being effectively insulated from air currents whereby to prevent dehydration of food products stored therein.

It will be apparent that if it is desired the rear vertically extending lip 18 may be increased or decreased in length as desired so as to properly restrain articles from falling from the hydrator when it is tipped forwardly into position shown in dotted lines.

In Fig. 5, I disclose a modified form of my invention wherein the space or recess 5 for accommodating pan 12 is located at the bottom edge of the door, the pan itself being beveled at 19 so as to provide the usual seal against the breaker strip of the refrigerator. In this modification, the pivot point 20 is located adjacent the rear of the pan for obvious reasons. It will be noted that in closed position of door 1 the pan 12 will be continually urged shut. Accordingly, a spring detent 14 acting in a somewhat less positive manner than in the modification of Fig. 1, by pressing at right angles against the relatively elongated folded-over lip 13, may be employed.

In Fig. 6, I illustrate a further modified embodiment of my invention, wherein a door recess 75 5 similar to that illustrated in Fig. 1 is utilized,

modified by a forwardly extending recess 21 cut in lower ledge 17. The pan pivot pintle 22 is arranged lower on the pan so that when the same is swung open into recess 21, as illustrated in dotted lines, the ledge 17 or recessed portion thereof provides a stop limiting further movement. In Fig. 6, the pan is likewise formed slightly differently to present a beveled edge 23 facilitating insertion of articles; accordingly the detent 24 is mounted slightly differently. 10

In Fig. 7, a still further modified form of my invention is illustrated, wherein a conventional hinge 25 is employed to pivotally mount the pan adjacent the edge of ledge 17, this hinge preferably permitting only 90° rotation of the pan 15 from operative closed position.

From the foregoing, it will be apparent that I have provided a hydrator pan and combination thereof with a refrigerator door which possesses distinct advantages. The same consumes a very 20 slight amount of the interior space of the refrigerator, is very effective in providing a dead air space insulating the door and preventing dehydration of fruits, vegetables and the like therein, and it is readily and quickly manipulated without inconvenience. Moreover, it is very attractive in appearance, readily installed in the conventional refrigerator door and will enhance the appearance and sales appeal of the same. 25

I have illustrated and described my improvements in embodiments which are very practical. I have not attempted to illustrate or describe other embodiments or adaptations as it is believed this disclosure will enable those skilled in the art to embody or adapt my improvements as may 35 be desired.

Having thus described my invention, what I claim as new and desire to secure by Letters Patent is:

1. In combination, a refrigerator door having 40 insulation therein, said door being substantially recessed and a portion of the insulation being omitted at the recess to provide a space adjacent the rear side thereof, a dehydration preventing pan for vegetables or the like pivotally 45 mounted in said space, said pan having side walls and being open on one side whereby to provide an opening for inserting and removing articles when the pan is in open position, the pan engaging the door in closed position whereby to effectively close said opening against the door and prevent circulation of refrigerator air currents in the pan, and resilient means for holding the pan in closed position.

2. In combination, a refrigerator door having 55 insulation therein, said door being substantially recessed to provide a space adjacent the rear side thereof, and a dehydration preventing pan pivotally mounted in said space and swingable therefrom to substantially horizontal position, said pan having retaining walls and being open on one side whereby to provide an opening for inserting and removing articles when the pan is in horizontal position, the open side of the pan engaging the door in closed position whereby to effectively close the same and prevent circulation of refrigerator air currents in the pan. 60

3. In combination, a refrigerator door having a substantial recess therein, and a dehydration preventing pan shaped to correspond to the shape 70 of said recess and pivotally mounted therein, said pan having side walls and an open side adapted to be swung against the rear of said recess to effectively close the pan and prevent air circulation therein. 75

4. In combination, a refrigerator door having a substantial recess therein, a dehydration preventing pan shaped to correspond to the shape of said recess and pivotally mounted therein, said pan having side retaining members and an open side adapted to be swung against one side of said recess to effectively close the pan and prevent air circulation therein, and means for yieldably holding the pan in closed position.
- 10 5. A refrigerator door having a dehydration preventing pan pivotally mounted thereon, said door having a pair of elongated slots for pivotally mounting the pan, said pan having pintles thereon receivable in said slots and swinging thereon in a vertical plane from closed to open position and vice versa, said pan having an open side adapted to be brought adjacent the door in closed position and effectively covered by said door in said position whereby to eliminate air circulation within the pan.
- 15 6. A refrigerator door having a dehydration preventing pan pivotally mounted thereon, said pan swinging in a vertical plane from closed to open position and vice versa, said pan having article retaining walls and an open side adapted to be brought adjacent the door in closed position and effectively covered by said door in said position whereby to eliminate air circulation within the pan.
7. A dehydration preventing element for refrigerators and the like, comprising a pan adapted to be pivotally mounted in an appropriate recess in the refrigerator, said pan being shaped to correspond to the shape of the recess and having an open side adapted to be effectively closed when the pan is in closed position in the recess, and means on the pan for manipulating the same from open to closed position and vice versa.
- 10 8. The combination of an insulated wall element comprising inner and outer walls and a filler of insulating material, the inner wall being conformed to provide a recess, and a receptacle mounted to close into said recess and having retaining side walls of substantial height and an 15 opening for the insertion and removal of articles closed when the receptacle is collapsed into the recess, the receptacle when closed constituting a complementary insulating element.
- 20 9. The combination of an insulated wall element conformed to provide a recess, and a receptacle mounted to close into said recess and having retaining side walls of substantial height and an opening for the insertion and removal of articles closed when the receptacle is collapsed 25 into the recess, the receptacle when closed constituting a complementary insulating element.
